ARRANGEMENT FOR REMOVING COILS OF WIRES, CABLES, AND THREADS OFF THEIR FORMING SPOOL

Marius Bernard Garet, Lyon, France, assignor to Etablissements G. Decombe, Lyon, France, a company of France

Filed Jan. 28, 1960, Ser. No. 5,163

Claims priority, application France Mar. 23, 1959

4 Claims. (Cl. 242—81)

Coils of wires, cables and threads are generally obtained by winding the latter over a disconnectable spool, so as to allow an easy removal of the coils obtained.

Upon stoppage of the forming spool, the operations to be executed for the removal of the coil are approximately as follows:

Release of one of the flanges of the forming spool.
Shrinking or collapsing of the drum of said spool.
Removal of the released flange.

Removal of the coil.
Resetting of the movable flange in its starting position.
Locking of said flange in said position.

Expansion of the drum into starting conditions.

These operations are executed by hand in a frequently repeated manner and they are consequently very tiring for the operator. Furthermore, they last some time and this leads to a waste of time—which is comparatively important, since the complete cycle of coiling operations is comparatively short.

The arrangement according to the invention for the removal of a coil of wire, cable or thread wound over a forming spool in accordance with the present invention allows reducing substantially the loss of time, whereby the productivity is increased.

To this end, the two flanges of the forming spool cooperate with stationary surfaces, in substantial alignment therewith and between which the coil which has just been executed is to slide out after cutting out of the connections holding the coil in position, which connections are constituted by the drum round which the coil is wound and by the pressure exerted by the coil on the inner surfaces of the flanges of the forming spool.

The accompanying diagrammatic drawings illustrate, by way of example, a preferred embodiment of the improved arrangement. In said drawings:

Fig. 1 is a longitudinal sectional view through line 1—1 of Fig. 2 of the arrangement as shown during the winding of a coil.

Fig. 2 is a transverse cross-section through line 2—2 of Fig. 1.

Fig. 3 is a longitudinal cross-section showing the location of the different parts of the arrangement, after an outward shifting of the drum out of the forming spool.

Fig. 4 is a similar longitudinal cross-section showing how the coil may be removed after removal of the drum out of the forming coil and shifting aside of one of the flanges.

The forming spool includes a stationary flange 2 carried by the spindle 3 revolvably mounted in the wall 4 of the casing. The inner surface of said flange forms a bearing for one of the edges of the cylindrical wall of the spool drum 5 over which the material 6 is wound. Said drum is rigid through its bottom 7 facing away from the wall 4 with a control rod 8 which serves for axially shifting the drum. The peripheral surface of the drum 5 slides freely inside the inner wall of the chamber 9 which serves as a housing for the drum. The cylindrical

wall 10 of said chamber is rigid with a movable transverse flange 11 and also with a carrier or sleeve 12 facing away from the inside of the chamber and carrying the pulley 13 through which the spool drum 5 is driven into rotation. A spring 14 acting on the outer transverse closing surface of the chamber 9 urges the latter towards the flange 2 together with the movable flange 11 rigid with said chamber and sleeve.

After the winding of the coil over the drum and in order that said coil may drop through the channel separating two stationary walls 15 and 16 forming substantial extensions of the corresponding flanges 2 and 11 of the coil-forming spool, it is necessary to make the drum 5 recede and to shift apart said flanges 2 and 11.

15 The drum 5 may be urged out of the formed coil into the bottom of its housing or chamber 9 (Fig. 3) under the action of the control rod 8 which is shifted to this end in the direction of the arrow 17. When the drum 5 has completely receded inside said housing 9, it may 20 be urged further in the same direction defined by the arrow 17, whereby its bottom 7 draws along with it the cooperating outer wall 10' of the chamber 9 together with the flange 11. Said movement increases, as illustrated in Fig. 3, the spacing between the flanges 2 and 25 11 and releases consequently the coil 6 which is no longer subjected to any lateral pressure. Since the drum has now executed its receding movement, the coil is no longer held and drops through the channel 18 between the walls 15 and 16, the opening into said channel being 30 completely released since the movable flange 11 of the forming spool is set in alignment with the stationary wall 16 and engages a recess 19 formed for this purpose in the said wall 16.

It is also possible in case the weight of the coil may 35 not be sufficient to make it drop freely through the channel 18 or to slide over one side thereof, to provide a pusher member, which is not illustrated, so as to further this dropping or sliding movement.

The channel 18 may also be provided with lateral deflecting members 20 (Fig. 2), the position of which is adjustable and which form the side walls of a hopper-shaped structure through which the coil may slide or be pushed.

Assuming a basket, box or the like container is positioned under the foot of the hopper or channel, the coil 45 may be immediately inserted in a package at the output of the winding machine.

Obviously, instead of resorting to a laterally shiftable drum round which the wire, cable or thread is to be wound, it is possible to provide a mere spindle engaging a spool body, the breadth of which is equal to that of the coils to be formed and which is brought into a suitable position to allow the winding of the material over it. The result is that, upon removal of the spindle, the coil 55 will drop or be pushed through the channel or hopper together with the spool body carrying it.

In practice and in order to allow a sufficiently broad range of operation, the coil-removing arrangement which has just been described may include means for adjusting the spacing between the flanges 2 and 11 and that between the stationary walls 15 and 16.

Obviously, the invention is by no means limited to the sole embodiment which has just been described and it covers all the modifications thereof falling within the scope of the accompanying claims. In particular, other means may be provided for shifting aside the drum of the forming spool and for spacing apart the flanges of said spool, with a view to obtaining a speedy removal of the coil which has been formed.

70 What I claim is:
1. In a machine for winding wire, cable or thread ma-

aterial, a forming spool including a revolvable drum over which the material is coiled and two flanges engaging laterally the drum and one of which is adapted to be shifted away from the other out of a coil-clamping into a coil-releasing position, means holding said drum in its operative position between the flanges and adapted to be shifted aside to release said drum, two stationary walls extending in parallelism with the two flanges and in substantial alignment therewith for the coil-releasing position of the latter, said walls forming together an output channel for the coil, and means for spacing the flanges apart to allow the passage, between them and into the space between the stationary walls, of the coil formed on the drum after shifting aside of the drum-holding means.

2. In a machine for winding wires, cables or threads, a forming spool including two flanges one of which is adapted to be shifted away from the other, a drum revolvably carried between said flanges and adapted to be shifted laterally out of the space separating the flanges, two parallel stationary walls extending substantially in parallelism with the two flanges and the spacing between which is slightly larger than the normal spacing between the flanges and forming together an output channel for the coil and means for shifting said one flange slightly away from the other to bring it into registry with the plane of the corresponding wall.

3. In a machine for winding wires, cables or threads, a forming spool including two flanges one of which is adapted to be shifted away from the other, a drum revolvably carried between said flanges and adapted to be shifted laterally out of the space separating the flanges, two parallel stationary walls extending substantially in parallelism with the two flanges and the spacing between

which is slightly larger than the normal spacing between the flanges and forming together an output channel for the coil and means controlled by the lateral shifting of the drum for shifting said one flange slightly away from the other to bring it into registry with the plane of the corresponding wall.

4. In a machine for winding wires, cables or threads, a forming spool including two flanges one of which is adapted to be shifted away from the other, a drum revolvably carried between said flanges and adapted to be shifted laterally out of the space separating the flanges, two parallel stationary walls extending substantially in parallelism with the two flanges and the spacing between which is slightly larger than the normal spacing between the flanges and forming together an output channel for the coil, a carrier rigid with said one flange, in which the drum is revolvably mounted and adapted to move in parallelism with the axis of the drum, means urging said carrier into movement to shift the flange carried by it towards said other flange and hold said flanges at their normal spacing equal to the breadth of the coil to be obtained, means rigid with the drum and adapted upon lateral shifting of the drum to move the carrier outwardly and thereby to urge the flange rigid with the latter away from the other flange to release the pressure on the coil.
